UNITED STATES PATENT OFFICE.

CHARLES M. HUFF, OF ALBION, WASHINGTON.

SHARPENING MACHINE.

Application filed June 12, 1922. Serial No. 567,794.

To all whom it may concern:

Be it known that I, CHARLES M. HUFF, a carpenter, citizen of the United States, residing at Albion, in the county of Whitman and State of Washington, have invented certain new and useful Improvements in Sharpening Machines, of which the following is a specification.

This invention relates to a sharpening machine and has for its principal object to produce a machine that can be easily transported and set up whenever it is necessary to use the same, and which is particularly adapted for sharpening band knives as used in threshing machines.

Another object of the invention is to provide a sharpening machine of the above mentioned character that can be adjusted to various positions so as to accommodate various kinds and sizes of knives which may have to be sharpened thereon.

A still further object of the invention is to produce a sharpening machine of the above mentioned character that can be knocked down and carried conveniently upon the farm implement with which it is to be used and which is provided with means for adjusting the same to various positions and which has driving means carried thereby that is adapted to be driven by the driving power used in the farming implement upon which the sharpening machine is carried.

A still further object of the invention is to provide a sharpening machine of the above mentioned character which is inexpensive in its manufacture, simple in construction, strong and durable.

Other objects and advantages of this invention will become apparent during the course of the following description.

In the accompanying drawings forming a part of this specification, and in which like numerals designate like parts throughout the same:

45 Figure 1 is a front elevation of the invention.

Figure 2 is a side elevation of the same.

Figure 3 is a perspective view of the auxiliary frame, and

50 Figure 4 shows one of the bracing elements.

In the drawings, wherein for the purpose of illustration is shown the preferred embodiment of my invention, the numeral 1 designates the base which consists of spaced longitudinal bars 2 and 3 which are held in

spaced relation by means of transverse bars 4 and 5.

A frame consisting of parallel side members 6 and 7 and a cross bar 10 is hingedly connected at its lower end to the base 1 by means of suitable strap hinges 8 and 9. The cross bar 10 is attached to the side members 6 and 7 at their upper ends and crossed diagonally extending brace rods 11 and 12 are further secured to the side members 6 and 7 of the frame so as to hold the same in rigid position. Supporting elements 13 and 14 are pivotally secured at their lower ends to the base 1 and their free ends are provided with elongated open slots 15 for the purpose of receiving threaded bolts 16 and 17 which are carried by the side members 6 and 7 of the frame. The purpose of these supporting elements 13 and 14 is to adjust the frame to permit the same to be held in a vertical position or at an angle to the vertical as desired.

After the frame has been adjusted to the proper angle thumb nuts 18 and 19 which are carried by the bolts 16 and 17 are then threaded on the bolts until they engage the sides of the bracing elements 13 and 14 to rigidly and securely hold the frame in the adjusted position. An auxiliary frame 20 consisting of side rails 21 and 22 is braced by means of cross arms 23 and 24. The side members 21 and 22 of the auxiliary frame 20 are provided with longitudinally extending tongues on their outer sides to slide within grooves formed in the inner sides of the side members 6 and 7 of the main frame. It will therefore be seen that the auxiliary frame is slidably mounted with relation to the main frame for the purpose hereinafter to be fully described.

Carried by the auxiliary frame 20 is a pulley wheel and bracket 27 which is mounted upon the top edge of the lower cross arm 23. Secured to the under side of the cross arm 10 of the main frame is an eye 28 for the purpose of attaching one end of the cable 29 thereto. The cable is adapted to travel over the pulley wheel 27 and the end thereof opposite to the end connected to the eye 28 is connected to a shaft 30 which is carried by the main frame and held thereon by means of suitable bearing brackets 31. This shaft 30 has one end terminating in a crank 32, which extends beyond one side of the frame, whereby the shaft 30 may be readily rotated to cause the cable 29 to be

wound upon said shaft, which in turn will cause the auxiliary frame 20 to move longitudinally of the main frame and thereby increase or decrease the height of the auxiliary frame.

Journalized in suitable bearings 33 and 34, which are carried at the top of the auxiliary frame 20, is a shaft 35. These bearings 33 and 34 which support the shaft 35 are secured to the auxiliary frame 20 by means of brackets 36. Secured to one end of the shaft 35 is a grinding wheel or sharpening wheel 37, which is held thereon by means of a suitable locking element 38. Arranged on the shaft 35 between the side members 21 and 22 of the auxiliary frame 20 is a pulley wheel 39 and trained over this pulley wheel 39 is a suitable driving belt 40. To further prevent the shaft 35 upon which is mounted the sharpening wheel 37 and the pulley 39, from side movement, suitable collars 41 and 42 are disposed on the shaft 35 and held thereon beside the side rails 21 and 22 of the auxiliary frame by set screws 43 and 44.

Ordinarily the sharpening machine is carried upon the agricultural implement in a folded position and when it is desired to use the same for sharpening various implements on the machine or whenever it is necessary to take the implements off the machine to sharpen them, the machine is taken from the agricultural implement upon which it is mounted and is set upon the ground in the manner shown in the drawings in Figs. 1 and 2. The belt 40 which drives the grinding wheel 37 mounted upon the shaft 35 is connected with any suitable driving means and may be connected to the driving shaft of the agricultural implement upon which the machine is carried. Any suitable power may be employed to operate the sharpening machine. Whenever it is necessary to adjust the main frame and auxiliary frame according to the desired angle, it can be readily done in the manner set forth in the above description. The grinding machine can be easily set up for the purpose of grinding

band knives or other implements desired and does not necessitate the use of a complicated and large machine.

It is to be understood that the form of my invention herewith shown and described is to be taken as the preferred embodiment of the same and as various changes in the size, shape and arrangement of parts may be resorted to without departing from the spirit of the invention and the scope of the subjoined claims.

Having thus described my invention what I claim as new and desire to secure by Letters Patent is:—

1. A portable grinding machine comprising a base, a main frame hingedly carried by the base, an auxiliary frame slidably mounted in the main frame, grinding means carried by the auxiliary frame, winding means carried by the main frame, and a flexible element connected to the winding means and to the auxiliary frame, whereby upon movement of the winding means, the auxiliary frame will be raised or lowered within the main frame.

2. A portable grinding machine comprising a base, a main frame hingedly secured to the base adjacent the forward end thereof including a pair of spaced uprights having channels formed in their inner faces defining guideways, means carried by the base for engaging the swinging frame to hold the same in adjusted relation to the base, an auxiliary frame slidably associated with the main frame including side bars and laterally extending guide ribs mounted in said guide channels means for adjusting the auxiliary frame in relation to the main frame, and a grinding wheel rotatably carried by said auxiliary frame.

In testimony whereof I affix my signature in presence of two witnesses.

CHARLES M. HUFF.
